(57) **CLAIM**

The ornamental design for a model aircraft, as shown and described.

DESCRIPTION

FIG. 1 is a front perspective view of a model aircraft showing my new design;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines are included for the purpose of illustrating portions of the model aircraft that form no part of the claimed design.
